UNITED STATES PATENT OFFICE.

CHARLES L. BETTS, OF NEW YORK, N. Y., ASSIGNOR TO R. E. DIETZ COMPANY, OF NEW YORK, N. Y.

DESIGN FOR A TUBULAR LANTERN.

43,415.

Specification for Design.

Patented Jan. 7, 1913.

Application filed April 29, 1912. Serial No. 693,978. Term of patent 14 years.

To all whom it may concern:

Be it known that I, CHARLES L. BETTS, a citizen of the United States, residing at New York, borough of Brooklyn, in the county of Kings and State of New York, have invented a new, original, and ornamental Design for Tubular Lanterns, of which the following is a specification.

The accompanying drawing is an elevation of a tubular lantern showing my new design.

The characteristic feature of this design consists of the shape of the lower portion of the lantern which comprises a base A, contracted upwardly in the form of an ogee,

a font having bulging or convex upper and lower portions *b* *c* and an intermediate cylindrical band *d*, and branches *E* having their lower horizontal portions *e* arranged on a level with the upper convex portion *b* of the font and extending from opposite sides thereof.

I claim:

The ornamental design for a tubular lantern, as shown and described.

CHARLES L. BETTS.
